AUTOMOTIVE VEHICLE REAR END WARNING LIGHT PANEL

Jack R. Hendrickson, Bloomfield Hills, Mich. 48013

Continuation-in-part of design application Ser. No. 7,526,
June 20, 1967. This application May 19, 1969, Ser.
No. 17,200

Term of patent 14 years

Int. Cl. D26—06

U.S. Cl. D48—32

FIGS. 1 and 2 are, respectively, perspective and rear elevational views of an automotive vehicle rear end warning light panel embodying my design;

FIG. 3 and 4 are, respectively, cross-sectional and rear elevational views thereof.

The broken line structure shown in FIGS. 1 through 4 is shown for illustrative purposes.

This is a continuation-in-part of application Ser. No. D. 7,526 filed June 20, 1967 and now abandoned.

I claim:

The ornamental design for an automotive vehicle rear end warning light panel, as shown and described.
